STOKER CONSTRUCTION

Royce L. Beers, Detroit, Mich., assignor to Detroit Stoker Company, Detroit, Mich., a corporation of Michigan

Application July 30, 1932, Serial No. 627,073

10 Claims. (Cl. 110--44)

This invention relates generally to stokers and refers more particularly to a wind box and tuyère structure for underfeed stokers of the multiple retort type.

5 In the accompanying drawings:

Figure 1 is a perspective view of a stoker construction embodying my invention;

10 Figure 2 is a fragmentary vertical sectional view through the stoker construction illustrated in Figure 1;

Figure 3 is a detail elevation of one of the wind boxes;

15 Figure 4 is an end elevation of the construction illustrated in Figure 3;

Figure 5 is a top plan view of the structure illustrated in Figure 3;

20 Figure 6 is a rear elevation of one of the end tuyère blocks;

Figure 7 is a side elevation of the block illustrated in Figure 6;

25 Figure 8 is a rear elevation of one of the intermediate tuyère blocks;

Figure 9 is a side elevation of the block illustrated in Figure 8.

30 Referring now to the drawings, A is the front wall of a furnace, and B are a plurality of retorts extending through and rearwardly from said wall. C are wind boxes set in the front wall A and bridging the retorts; D and E respectively are tuyère blocks within the boxes C; and F are tuyère blocks arranged in rows between the retorts B from the boxes C to the rear ends of the retorts. As shown, the retorts B are substantially 35 trough-shape in configuration and are arranged in substantially parallel formation above a suitable wind chamber G. The tuyère blocks F are hollow and are adapted to receive air from the wind chamber G. Such blocks are provided with outlets 1 for the air and collectively form ducts for the air from the chamber G to the wind boxes C in the front wall A. Preferably each box C is a hollow casting and is inverted U-shape in configuration. The legs 2 and 3 respectively of the boxes rest upon and are secured to the longitudinal edges of the retorts B. The arched portion 4 and the front, top and end walls 5, 6, 7 and 8 respectively of each box are imperforate but the rear wall 9 is provided above and upon opposite sides of the arched portion 4 with connecting openings 10, 11 and 12 respectively. Preferably the opening 10 extends from one end wall to the other but is spaced from the top wall 6 and arched portion 4 so that relatively narrow wall portions 13 and 14 respectively are provided. As shown in Figure 4, the rear wall 9 from the uppermost edge of the arched portion 4 to the lower ends of the legs 2 and 3 is offset rearwardly relative to the portions 13 and 14 and end walls 7 and 8. Thus ledges 15, 16 and 17 respectively are provided in rear of the portion 14 and at the lower ends of the

legs 2 and 3. Ledges 18 and 19 respectively are also provided upon the front walls 5 of the boxes adjacent the lower ends of the legs 2 and 3.

35 The tuyère blocks D are located in the legs 2 and 3 at opposite ends of the boxes while the tuyère blocks E are located between the blocks D and above the arches 4. Preferably each block D has a substantially flat body portion 20 and a web portion 21. As shown, the body portions 20 rest against the rear faces of the uppermost portions 13 of the rear walls and against the rear edges of the end walls 7 and 8 and abut the upright edges 22 and 23 respectively of the offset portions of the rear walls, while the web portions 21 rest upon the ledges 18 and 19 respectively and have substantially U-shaped recesses 24 in their upper ends receiving the portions 13 of the rear walls 9. Likewise each block E has a substantially flat body portion 25 and a web portion 26, however, these blocks are much shorter than the blocks D. As shown, the body portions 25 of the blocks E rest on the ledges 15 and against the rear faces of the uppermost portions 13 of the rear walls, while the web portions 26 are provided in their upper and lower ends with substantially U-shaped recesses 27 and 28 respectively that receive the portions 13 and 14 of the rear walls. Preferably the construction and arrangement of the blocks D and E and rear walls 9 of the boxes are such that the faces 30, 31 and 32 respectively of the blocks D and E and offset portions of the rear walls 9 are substantially flush with the rear face 33 of the furnace wall A. Moreover, the construction and arrangement of the blocks D and the leg portions 2 and 3 of the boxes are such that the portions L and M respectively of the openings 11 and 12 below the ledges 18 and 19 are uncovered and receive air from the tuyère blocks F. To permit this air to flow rearwardly from the boxes C into the furnace above the retorts the upright edges of the body portions 20 and 25 respectively of the blocks have segmental openings 34 and 35, preferably semi-circular in form, disposed in opposed relation and forming circular openings for the passage of the air. Thus the air discharged therefrom supports combustion of any gases given off by the fuel upon its initial introduction into the retorts within the furnace. In practice the wind boxes C may be readily mounted upon the retorts B and may, if desired, be bolted thereto, suitable openings 40 and 41 respectively being provided in the lower ends of the leg portions 2 and 3 for this purpose. As a result the boxes C are individually mounted and any one of them may be removed for repairs or replacements without disturbing the others. Likewise the blocks D and E may be readily assembled within or removed from the boxes C. For instance, one of the blocks D may be inserted into the opening 12 by first 45 engaging the recess 24 with the wall portion 13

and then swinging the lower end of said block into the box so that said lower end will seat upon the ledge 19. The blocks E may then be inserted one at a time in the opening 11 so that the recesses 27 and 28 will receive the wall portions 13 and 14 whereupon such blocks may be moved sideways on the wall portions 13 and 14 toward the block D in the opening 12. The other end block D may then be engaged with the wall portion 13 and inserted in the opening 11 to complete the assembly. Thus the construction and arrangement is such that the intermediate blocks E are held in place by the end blocks D but may be removed upon the removal of any one of the end blocks D from the said box C. This provides a sectional and removable tuyère block assembly wherein the parts exposed to the fire may be individually removed and replaced. Moreover, the manner in which the blocks are held in place is such that the assembly or removal of the blocks may be easily and quickly made.

What I claim as my invention is:

1. In a stoker, a hollow wind box having a rear wall provided with a longitudinally extending slideway for tuyère blocks and provided below and at opposite ends of said slideway with openings through which the tuyère blocks aforesaid may be moved and into which other tuyère blocks may be received.

2. In a stoker, a hollow wind box having a rear wall provided with a longitudinally extending slideway for tuyère blocks, a ledge below said slideway for supporting portions of said tuyère blocks, and an opening at one end of the slideway through which said tuyère blocks may be moved to and from the slideway and into which another tuyère block may be received, said wind box having a front wall provided with means for supporting the last mentioned tuyère block.

3. In a stoker, a hollow wind box having a rear wall provided with a longitudinally extending slideway for tuyère blocks of one design, and an opening at one end of the slideway through which said tuyère blocks may be moved to and from the slideway and into which a tuyère block of another design may be received.

4. In a stoker, a hollow wind box having a rear wall provided with a longitudinally extending opening for tuyère blocks, vertically extending openings for tuyère blocks at opposite ends of said longitudinally extending opening, and an offset portion between said vertical openings providing a ledge below the longitudinally extending opening for supporting portions of the tuyère blocks in the longitudinally extending opening and upright portions for engagement by the tuyère blocks in the vertical openings.

5. In a furnace, the combination with a plurality of spaced elongated retorts, and tuyère sections spanning the spaces therebetween and forming therebeneath air chambers, of a wind box tuyère structure spanning the retorts at their charging ends and defining the charging openings thereto, comprising a plurality of hollow boxes, each having top, end, front and rear walls, and an arched bottom wall defining with said end walls legs which support the boxes on the retort side walls, and which communicate with the air spaces therebetween, each rear wall comprising a plate provided with an approximately inverted U-shaped opening, the opposed edges of which are substantially parallel, a plurality of tuyère blocks slidably mounted intermediate the

leg portions of each U-shaped opening, and an end tuyère block removably mounted in each leg portion and holding said intermediate blocks against sliding movement, said boxes being mounted with their end walls in abutting relationship with each other.

6. In a stoker, a hollow wind box having top, end, front and rear walls and an arched bottom wall defining with said end walls supporting legs, said rear wall comprising a plate provided with an approximately inverted U-shaped opening, the opposed edges of which are substantially parallel, a plurality of tuyère blocks slidably mounted intermediate the leg portions of the U-shaped opening, and an end tuyère block removably mounted in each leg portion and holding said intermediate blocks against sliding movement.

7. In a stoker, the combination with a plurality of laterally spaced elongated retorts, and longitudinally extending air ducts between said retorts, of means for conducting air from the ducts to points above the retorts, including wind boxes extending upwardly from the retorts at the forward ends of the ducts, and having openings in their rear walls communicating with and adapted to receive air from the forward ends of said ducts, the rear walls of said wind boxes comprising plates having approximately inverted U-shaped openings, and removable tuyère blocks within said openings and forming portions of the rear walls of said wind boxes, said tuyère blocks being provided above said ducts with means for directing rearwardly over the retorts the air received in the first mentioned openings.

8. In a furnace, the combination with a plurality of laterally spaced retorts and tuyère sections spanning the spaces therebetween and forming therebeneath air chambers, of a wind box tuyère structure spanning the retorts at their charging ends and defining charging openings thereto, comprising a plurality of hollow boxes, each having top, end, front and rear walls, and an arched bottom wall defining with said end walls supporting legs which rest on the retort side walls and which communicate with the air spaces therebetween, the rear walls of said boxes having openings therein, and tuyère blocks arranged in said openings and having openings through which air from the interior of said boxes may be discharged rearwardly over said retorts.

9. In a stoker, a hollow wind box having top, bottom, end, front and rear walls, a portion of the bottom wall being arched and defining with the end, front and rear walls supporting legs, said rear wall having an opening therein, opposite ends of which are adjacent the end walls, end tuyère blocks removably mounted in said opening at opposite sides of the arched portion aforesaid, and a plurality of tuyère blocks arranged side by side in the opening over the arched portion between and held against displacement by the end blocks just mentioned.

10. In a stoker, a hollow wind box having top, bottom, end, front and rear walls, said rear wall having an approximately inverted U-shaped opening therein, the opposed edges of which are substantially parallel, a plurality of tuyère blocks mounted in the opening intermediate the leg portions of the U, and an end tuyère block removably mounted in each leg portion of the U and holding said intermediate blocks against displacement.

ROYCE L. BEERS.
